UNITED STATES PATENT OFFICE.

BURLAN S. BARBER, OF MINONK, ILLINOIS.

TABLE-CLOTH SUPPORT.

1,277,827.

Specification of Letters Patent. Patented Sept. 3, 1918.

Application filed November 28, 1917. Serial No. 204,390.

To all whom it may concern:

Be it known that I, BURLAN S. BARBER, a citizen of the United States, residing at Minonk, in the county of Woodford, State 5 of Illinois, have invented a new and useful Table-Cloth Support; and I do hereby declare the following to be a full, clear, and exact description of the invention, such as will enable others skilled in the art to which 10 it appertains to make and use the same.

This invention relates to an improved table cloth support, and one of the objects of the invention is the provision of an improved support of this kind, which may be 15 manufactured for a small cost and sold at a reasonable profit.

On large farms or ranches, the food in dishes is placed on the table, and heretofore a table cloth or the like is thrown 20 thereover, and when the hands working on the farm or ranch come in at meal time the cloth is removed, allowing access to the food on the table. In this way the cloth very often contacts with the food itself.

25 Therefore, another object of the invention is the provision of an improved, simple, and efficient support, preferably one at each end of the table, or as many as may be desired, consisting of a single length of yield- 30 able wire bent to form an arch and provided with spring coils, and having means at its ends to clamp in engagement with the opposite longitudinal portion of the marginal edge of the table top, to support the table 35 cloth in a raised or arched position over the food.

In practical fields the detail of construction may necessitate alterations falling within the scope of what is claimed.

40 The invention comprises further features and combination of parts as hereinafter set forth shown in the drawings and claimed.

In the drawings:—

45 Figure 1 is a view in perspective of a table top disclosing the improved support applied thereto.

Fig. 2 is a transverse sectional view of the table top showing the support in elevation.

50 Fig. 3 is an enlarged detail view in perspective of one end of one of the supports.

Referring more especially to the drawings, 1 designates the support as a whole,

which consists of a single length of yieldable or spring wire, which may be bent 55 in any suitable shape, preferably arched as illustrated. The single length of wire is provided with one or more spring coils or twists 2 in order to insure additional resiliency or yieldability. Each end of the 60 wire is bent at 3, 4 and 5, thereby forming an arm 6 consisting of double thicknesses of wire, to engage the upper face of the table top. The wire beyond the bend 5 is again bent as at 7, and beyond this bend 65 the wire is turned in the form of a circular clamping portion or arm 8. In this manner, viewing the support in side elevation, a U-shaped end is formed, to straddle the edge portion of a table top. In other words 70 the circular arm or portion 8 engages the under face of the table top, whereas the arm 6 engages the upper face of the table top, thereby holding the support 1 rigidly in position, there being a support at each end 75 of the table, whereby the table cover may be supported in an arch position over the food. If desired one table cloth may engage the table top proper with the food thereon, while another cloth may be thrown over the 80 supports. In this way the clamping members at the ends of the support may hold the cloth that contacts with the table top as well as supporting the second cloth over the food. The opposing and abutting parts of 85 each looped arm 6 may be separated or sprung apart to receive and clamp a portion of the table spread therebetween, thereby preventing accidental displacement of the spread.

90 The invention having been set forth what is claimed as new and useful is:—

A table spread support comprising a frame constructed from a single length of spring wire material and being arched and 95 resilient and to extend from one side of the table top to the other, said frame have spring coils, one near each end, each end of the frame beyond the coil being bent upon itself to form a loop arm overhanging the 100 upper surface of the table top, the opposite adjacent sides of each looped arm adapted to be separated to receive and clamp therebetween said table spread, said end portion beyond the loop arm being bent U-shaped to 105 straddle the edge portion of the table top,

the lower arm of said U-shaped portion terminating in an enlarged circular spring ring having an unattached extremity and adapted to yieldably engage under the table top, 5 whereby the arched frame may be supported in an upright position should one end of the frame be detached.

In testimony whereof I have signed my name to this specification in the presence of two subscribing witnesses.

BURLAN S. BARBER.
